UNITED STATES PATENT OFFICE.

CHARLES W. HARVEY, OF NEW LONDON, CONNECTICUT.

FLASH LIGHT.

Application filed January 17, 1922. Serial No. 529,843.

To all whom it may concern:

Be it known that I, CHARLES W. HARVEY, a citizen of the United States, residing at New London, in the county of New London, 5 State of Connecticut, have invented a new and useful Flash Light; and I do hereby declare the following to be a full, clear, and exact description of the invention, such as will enable others skilled in the art to which it appertains to make and use the same.

The invention relates to flash lights of the portable type and has for its object to provide a flash light of this character which is small, durable and so constructed that an 15 electric light will be lighted through the medium of current generated by a generator, said generator having a gear train connection with a spring motor. Also to provide a rotatable sleeve forming a handle member, 20 which sleeve may be utilized for winding the spring motor. It has been found that where batteries are used in flash lights that it is necessary from time to time to buy new batteries which are expensive and which cannot be 25 obtained at all times in different parts of the country, therefore it is an object of the invention to provide a flash light wherein the current is obtained from a generator operated by a spring motor within the casing 30 of the light.

A further object is to provide the cylindrical casing with a removable lens carrying member which is threaded to the casing, said lens carrying member being provided with 35 a disc threaded therein, which disc is provided with a centrally disposed threaded aperture for the reception of an electric light bulb socket.

With the above and other objects in view 40 the invention resides in the combination and arrangement of parts as hereinafter set forth shown, in the drawings, described and claimed, it being understood that changes in the precise embodiment of the invention, 45 may be made within the scope of what is claimed without departing from the spirit of the invention.

In the drawings:

Figure 1 is a longitudinal sectional view 50 through the flash light.

Figure 2 is a vertical transverse sectional view taken on line 2-2 of Figure 1.

Figure 3 is a transverse sectional view 55 through the light taken on 3-3 of Figure 1.

Figure 4 is a transverse sectional view

through the flash light taken on line 4-4 of Figure 1.

Referring to the drawings, the numeral 1 designates a cylindrical casing, the rear end 2 of which is enlarged and has secured thereto by means of rivets 3 one end of a coiled spring 4 which forms a spring motor. The other end of the coiled spring is secured at 5 to a drive shaft 6. The forward end 7 of the shaft 6 drives a gear train 8 through the 60 medium of the gear 9, said gear train being so constructed that the drive shaft 10 which drives the generator 11 will revolve preferably from two thousand five hundred to three thousand revolutions per minute which is 65 sufficient for the generator 11 which is an alternating current multipolar generator to generate electric current sufficient to light the electric bulb 12 when the holding disc 13 is released and the generator allowed to 70 revolve under the control of the spring motor. The disc 13 is engaged by a plunger 14, which plunger when forced downwardly at its finger engaging end 16 holds the disc 13 against rotation and consequently 75 prevents operation of the generator 11. How- 80 ever after the motor has been wound by rotating the handle sleeve 17 in the rectangular shaped aperture 18 of which the rectangular shaped portion 19 of the shaft 6 is dis- 85 posed, said generator will be rotated through the gear train 8, thereby generating current which may be taken off by a conventional form of collector ring 20 from which ring one side passes to the disc 13 and the 90 other side to the spring arm 21 located forwardly of the disc. Threaded at 22 to the forward end of the cylindrical casing 1 is a flared lens carried member 23 in which a lens 24 is disposed. The lens carrying mem- 95 ber 23 has interiorly threaded therein at 25 a disc 26. The disc 26 is preferably threaded into the flared member 23 from the rear side thereby allowing the disc to be easily and quickly placed in position or removed, 100 and by placing the disc 26 in the flared member 23, said disc and lens 24 are removed at the same time from the device when it is desired to repair or otherwise fix the generator and its adjacent mechanism. The electric 105 bulb 12 has its socket 27 threaded into the threaded opening 28 of the disc 26 and its rear end in engagement with the spring arm 21. If so desired a pawl 29 may be pro- 110 vided on the interior of the enlarged portion

2 of the casing 1, which pawl may be placed in engagement with the teeth 30 of the ratchet wheel 31 carried by the drive shaft 6 for holding the drive shaft against rotation and consequently holding the motor against unwinding.

From the above it is to be seen that a spring actuated generator light is provided, which light is simple in construction and so 10 constructed that the use of a battery is eliminated and the device may be continuously used until the parts are worn out.

The invention having been set forth what is claimed as new and useful is:-

15 The combination with a flashlight comprising a cylindrical casing having its rear end open, an electric generator within the forward end of said casing, a spring motor in the rear open end of the casing for operating said generator, an electric bulb lighted by said generator, a drive shaft for said 20 spring motor, of means whereby said spring

motor may be wound, said means comprising a cylindrical cup shaped housing rotatably mounted on the rear end of the cylindrical casing and having its bottom in close relation to the rear end of the casing, the bottom of the cup shaped cylindrical member being centrally attached to the motor shaft, a ratchet wheel carried by said shaft 25 and located between the motor and the bottom of the cup shaped member and a pawl pivotally connected to the inner periphery of the cylindrical casing adjacent its rear open end and cooperating with the ratchet 30 and forming means for preventing retrograde movement of the spring motor shaft.

In testimony whereof I have signed my name to this specification in the presence of two subscribing witnesses.

CHARLES W. HARVEY.
